Des. 182,931
Patented May 27, 1958

182,931

HOUSING FOR A WINDOW MOUNTED VENTILATING FAN

Viktor Schreckengost, Cleveland Heights, Ohio, assignor
to The Murray Ohio Manufacturing Company, Cleve-
land, Ohio, a corporation of Ohio

Application November 20, 1956, Serial No. 43,858

Term of patent 14 years

(Cl. D26—7)

FIG. 1

Des. 182,931

PAGE 2

FIG. 2

FIG. 3

FIG. 4

Fig. 1 is a perspective view of a housing for a window mounted ventilating fan, showing my new design;

Fig. 2 is a front elevational view;

Fig. 3 is a side elevational view; and

Fig. 4 is a top plan view thereof.

I claim:

The ornamental design for a housing for a window mounted ventilating fan, substantially as shown.
